UNITED STATES PATENT OFFICE

2,434,722

RAILWAY SWITCH LOCKING DEVICE

Rubertus W. Rutledge, Morganton, and Fred P.
Higginbotham, Black Mountain, N. C.

Application January 15, 1945, Serial No. 572,936

4 Claims. (Cl. 246—401)

1

This invention relates to a novel safety device in the form of a ready-to-use switch attachment so made as to accommodate the existing or stock part, whereby to permit it to be installed for use in association with conventional switch and track equipment, this without requiring any alterations in the existing parts.

The primary purpose of the invention is to provide a simple and expedient attachment which is characterized by a safety clamp which is so constructed and arranged as to prevent the switch points from separating and derailing the train under certain circumstances and conditions.

More specifically, we have evolved and brought into being a practicable and readily applicable safety device which is supplemental to the usual switch stand and lever, the same serving to grip the adjacent switch point and to hold it against the main rail when the switch is closed, whereby to achieve the feature of safety above-mentioned.

Another object of the invention is the provision of a safety attachment for cross-ties, the same being constructed and arranged to coact with the free end of the lever, that is, the lever which is employed on the switch and signalling stand, thus providing an arrangement which will secure a switch point in its closed position even though the switch stand or its appurtenances accidentally break, as is often the situation.

Another object of the invention is to provide a simple, ingenious and practicable attachment which not only makes the railroad safer for fast trains, but which is advantageous in that it is susceptible of manufacture and installation with a minimum of expense attending such requirements.

Other features and advantages to become more readily apparent from the following description and the accompanying illustrative drawing.

In the drawing, wherein like numerals are employed to designate like parts throughout the views:

Figure 1 is a perspective view showing a fragmentary portion of a railroad track construction including the conventional lever equipped semaphore stand and detailing the improved attachment cooperable with the lever of the stand and switch point.

Figure 2 is a section taken approximately on the plane of the line 2—2 of Figure 1, this looking in the direction of the arrows.

Referring now to the drawing, the old parts are denoted by reference letters and the new parts by reference numerals it will be observed

2

that the conventional track rails are indicated at A and the supporting cross-ties at B. The switch points are denoted by the letters C. The switch stand, which is conventional, is indicated generally by the character D and this includes the usual rotary signalling semaphore E and ball-equipped operating lever F. As stated, these are old parts commonly in use on railroads.

The attachment comprises an arm 3 of appropriate material and length. This is provided at its outer end with a notch 4 which is so constructed and arranged as to accommodate the adjacent free end portion of the lever F. On the opposite end of the arm is provided a substantially U-shaped safety clamp or clip 5. This is so constructed (see Figure 2) as to permit its upstanding ends to embrace the base flange of the main rail and the half-flange of the switch points. The safety clip is urged to position by 10 the tilting of the arm 3 and the weight of the weighted lever F on the outer end of said arm. It is disengaged and forced away from the rails by the coiled spring 6. To accomplish this the intermediate portion of the arm is pivotally mounted as at 7 in and between ears on a stirrup-like adapter fixture 9. That is to say, the intermediate portion 10 sits down on a plane between the cross-ties and carries the ears 8 which, in turn, serves to pivotally mount the arm. The 20 laterally offset end portions 11 reach up over and anchor upon the ties.

In operation it is obvious that when the switch lever is thrown in opposite directions not shown in the drawing, the safety clamp or clip 5 is 30 thrown down clear of the rails by the release spring, thus allowing the rails to be shifted so that the train can get into the siding off the main line. When the train is at the siding and the switch lever on all switches is thrown into 40 the main line in clear position, it hits the operating arm and thus restores the safety attachment into its full and retaining position shown in Figures 1 and 2.

45 The structure is such that it fits between the ties and does not offer any projections susceptible of easy breakage or dislocation. It is exceedingly simple, easy to put in position, and prepare, and otherwise aptly fitted for the purposes intended.

A careful consideration of the foregoing description in conjunction with the invention as illustrated in the drawing will enable the reader to obtain a clear understanding and impression 55 of the alleged features of merit and novelty suffi-

cient to clarify the construction of the invention as hereinafter claimed.

Minor changes in shape, size, materials and rearrangement of parts may be resorted to in actual practice so long as no departure is made from the invention as claimed.

We claim:

1. In a structural assemblage of the class described, in combination, a track structure embodying spaced parallel complementary cross-ties, standard rails mounted for operation atop said cross-ties, switch points also mounted on said cross-ties and arranged for coaction with predetermined portions of said rails, a conventional type switch stand, a lever mounted for operation on said switch stand, a switch point retaining and releasing arm, means fastened on at least one of said cross-ties and supporting said arm, said arm being disposed in parallelism alongside a coacting cross-tie and hingedly mounted on said means and operating within the confines of the space existing between adjacent surfaces of said cross-ties, the outer end of said arm being provided with a notch situated adjacent outer ends of the cross-ties, an end portion of said lever being seated in said notch and adapted to engage and depress the outer end of the arm when said lever is in one of its extreme positions, a point latching clip on the inner end of said arm, said clip being of U-shaped form and partially embracing one of said rails and the adjacent switch point when the outer notched end of said arm is depressed by said lever, and a coiled spring mounted in said clip and interposed between the clip and said one rail for normally urging the clip in a direction away from the rail and switch point.

2. An attachment of the class described comprising an elongated rectilinearly straight arm adapted to be placed in a horizontal position parallel to a standard cross-tie and provided at its outer end with means to accommodate and coact directly with the shank portion of the usual weighted lever employed in connection with a conventional type railway switch stand at a time when said lever is in a locked-down position, bracket means for hingedly attaching the intermediate portion of said arm to a supporting cross-tie, a U-clip secured rigidly on the inner end of said arm, said clip being adapted to partially embrace a standard track rail and switch point

coactable with said rail when the outer end of said arm is depressed by said lever, and means to urge said clip away from embracement of said rail when said lever is disengaged from said arm.

5. An attachment of the class described comprising an elongated rectilinearly straight arm adapted to be placed in a horizontal position parallel to a standard cross-tie and provided at its outer end with means to accommodate and coact directly with the shank portion of the usual weighted lever employed in connection with a conventional railway switch stand at a time when said lever is in a locked-down position, bracket means for hingedly attaching the intermediate portion of said arm to a supporting cross-tie, a U-clip secured rigidly on the inner end of said arm; said clip being adapted to partially embrace the base of a standard track rail and switch point coactable with said rail when the outer end of said arm is depressed by said lever, and means to urge the clip away from embracement of said rail when said lever is disengaged from said arm, said means comprising a coiled spring mounted within the confines of said U-clip, said spring being of a normally expandible type and being adapted to contact a track rail and serving to normally urge said clip, when the outer end of said arm is free of pressure from said lever, to a position which serves to disengage said clip from said rail and switch point.

- 10 20 25 30 35 40 45 50 55 60 65 70 75 80 85 90 95 100
4. The structure specified in claim 3, said bracket means being a U-shaped hanger and said hanger being adapted to be mounted in an operative position between said cross-ties.
